UNITED STATES PATENT OFFICE.

THOMAS JOHNSON AND WILLIAM G. ROBISON, OF COLDWATER, MICHIGAN.

CAR-CO尤LING.

SPECIFICATION forming part of Letters Patent No. 248,707, dated July 5, 1881.

Application filed March 23, 1881. (No model.)

To all whom it may concern:

Be it known that we, THOMAS JOHNSON and WILLIAM GABRIEL ROBISON, citizens of the United States, residing in the city of Coldwater, 5 in the county of Branch and State of Michigan, have invented a new and useful Car-Coupling Machine, of which the following is a specification.

Our invention relates to improvements in 10 car-coupling machines in which one or more coupling-hooks are used in connection with bumpers and levers; and the object of our improvement is, first, to provide a safe and convenient method of coupling cars, by which the 15 danger to life and limb will be obviated; and, second, to do away with the necessity of employing the amount of help heretofore necessary in the running of trains of cars, and especially those used in the carrying of freight.

20 We attain these objects by the mechanism illustrated in the accompanying drawings, in which—

Figure 1 is a view of a portion of the coupler attached to the end of the car. Fig. 2 is a front 25 view of the car with a part of the coupler and levers attached thereto. Fig. 3 is a top view, representing the coupling-hooks.

The letters of reference refer to the same parts in each figure.

30 A is the bumper, made of iron, running under the car lengthwise a sufficient distance for practical purposes.

B refers to hooks made of iron or steel, of sufficient strength for practical use. They are 35 held in position by bolts running through the bumpers A in a horizontal position.

C represents bolts running through the bumpers horizontally.

D represents levers attached to the sill of the car by bolts, as shown by letters E E. 40 Said levers are made of iron and crooked sufficiently to comply with requirements of the structure to which they are attached, their use being to uncouple said hooks, as shown in letters B B.

45 F represents the end of hooks, beveled from the center back, so as to prevent the hooks meeting when coupling, and to allow them to pass each other on one side or the other before falling into the bumper when the coupling is 50 complete, said hooks working freely on bolts C C, before referred to.

G represents the opening or cavity in the outer end of the bumper, to allow the insertion of the link commonly used, when desired.

55 H represents the cavity or opening in the bumpers, to admit the hooks when meeting to produce a couple.

Having thus fully described our invention, what we claim, and desire to secure by Letters 60 Patent, is—

The combination, in a car-coupler, of the bumpers, as represented in letters A A, the hooks, as represented in letters B B, the lever, as shown in letters D D, and the bevel on hooks, 65 as shown in letter F.

THOMAS JOHNSON.
WILLIAM G. ROBISON.
